Primary Examiner — S. Bryan Reinholdt, Jr.*(74) Attorney, Agent, or Firm* — Jose Cherson Weissbrot(57) **CLAIM**

The ornamental design for a double straw lid, as shown and described.

DESCRIPTION

FIG. 1 is a top perspective view of a double straw lid, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a top perspective view showing the double straw lid, in folded state.

The evenly spaced broken lines and the areas within them in the drawings depict portions of the double straw lid, that form no part of the claimed design. The dot-dash broken lines in FIG. 1 depict portions of the double straw lid and boundaries of the claim that form no part thereof.
